ROTARY BRUSH

Leo J. Rousseau, Grosse Pointe Park, Mich., assignor to Minit-Man, Inc., Detroit, Mich., a corporation of Michigan

Application September 23, 1950, Serial No. 186,445

2 Claims. (Cl. 15—183)

1

This invention relates to brushes and, in particular, to rotary brushes such as are used, for example, in washing vehicles.

One object of this invention is to provide a rotary brush construction in which the brush bars containing the brush bristles are held firmly in position in their rotatable supports without the necessity of using retaining hoops or rings in order to prevent radial displacement of the brush bars.

Another object is to provide a rotary brush construction wherein the brush units, when worn, and replaced, are more quickly and easily removed than has hitherto been possible.

Another object is to provide a rotary brush construction in which the brush units include bristles inserted in elongated channel-shaped brush bars which are in turn inserted endwise through circumferential undercut slots in spaced rotary discs mounted on a rotary shaft in such a manner that the overhanging portions of the peripheries of the discs hold the brush bars immovably against radial displacement.

In the drawings:

Figure 1 is a central vertical section through a rotary brush according to one form of the invention, taken along the line 1—1 in Figure 2;

Figure 2 is an end elevation of the rotary brush shown in Figure 1;

Figure 3 is a side elevation of one of the brush unit supporting discs used in the rotary brush of Figures 1 and 2;

Figure 4 is a cross-section taken along the line 4—4 in Figure 3;

Figure 5 is an enlarged fragmentary cross-section through the bottom of the brush units adjacent one of the supporting discs, showing the overhanging construction for holding the brush units in place;

Figure 6 is a central vertical section through a modified rotary brush, according to another form of the invention, taken along the line 6—6 in Figure 7;

Figure 7 is a top plan view of the rotary brush shown in Figure 6;

Figure 8 is a bottom plan view of a brush bar spacing member used in the rotary brush of Figure 6; and

Figure 9 is a vertical section taken along the line 9—9 in Figure 8.

Hitherto, in conventional types of rotary brushes, it has been found difficult to retain the bristles or brush units firmly in position against accidental dislocation and at the same time to facilitate repair or replacement of the bristles as

2

they become worn or broken. Certain prior brushes have used retaining rings or hoops which are intended to hold the bristles in position, but these hoops are subjected to a considerable strain during use by reason of the pressure exerted upon them, and the breakage of such a hoop releases the bristles or brush units so that the machine must immediately be shut down for repairs, or it causes damage to the machine or article which it is washing and results in a hazard to the safety of the operator. In other prior brushes, the brush units have been bolted in position, but this arrangement has likewise proved unsatisfactory because of the large number of bolts which must be removed in order to replace the brush units or bristles.

The present invention solves these problems by providing a rotary brush having a hub structure consisting of axially spaced circumferentially notched discs mounted on a rotatable shaft, the notches in the circumference of each disc having overhanging opposite edges which prevent removal of the brush units in a radial direction and hold them effectively in place. The brush units have channel-shaped brush bars or backs in which the loop-shaped or U-shaped bristles are held by means of a retaining rod in each brush bar or back, the latter being inserted endwise and held in position against endwise motion by one or two retaining rings. These retaining rings, however, are substantially free from strain since they are not required to hold the brush units in assembly, this being done by the overhanging edges of the circumferential notches, which are undercut for this purpose. The multiple bolts of prior brushes have been eliminated, and to replace a brush or an entire set of brushes, it is merely necessary to remove the two retaining rings or hoops and slide the brush units axially out of the undercut peripheral grooves and to insert a new brush unit or set of brush units in the reverse manner.

Referring to the drawings in detail, Figures 1 and 2 show a rotary brush, generally designated 10, according to one form of the invention as consisting generally of a hub structure 11 with brush units 12 attached thereto at intervals around the periphery thereof. The hub structure 11 consists of a rotary shaft 13 having a diametral slot 14 at one end thereof and having a plurality of spaced discs 15, four being shown for purposes of illustration, secured to the shaft 13 at spaced locations along it. The discs 15 have central holes 16 (Figure 3) for receiving the shaft 13 and 55 are secured thereto as at 17 by welding or other

appropriate means of attachment. Each disc 15 is provided with a multiplicity of circumferentially-spaced undercut notches or slots 18 having approximately U-shaped inner portions 19 and overhanging opposite edges 20 formed as a result of the undercut construction. The overhanging opposite edges 20 provide retaining shoulders 21 which hold the brush units 12 in position in the manner explained below. A collar 22 (Figure 1) is welded or otherwise secured to the shaft 13 near the end opposite to the end having the slot 14.

Each brush unit 12 (Figures 1 and 5) consists of an elongated channel-shaped brush back or brush bar 25 having an external cross-section substantially the size of the inner portion 19 of the notch or slot 18, with a suitable clearance sufficient to permit the brush bars 25 to be slid into and out of the notches or slots 18. The free edges 26 of the brush bars or backs 25 are so located that they engage the abutment shoulders 21 formed by the overhanging edges 20 of the notches or slots 18 to retain the brush bars or backs 25 firmly in position (Figure 5). The side portions 27 of the brush bars or backs 25 are substantially parallel and are interconnected by the bottom portion 28.

The bristle assembly 30 of each brush unit 12 is made up of U-shaped or loop-shaped bristles 31 having their side portions 32 interconnected by the portions 33, the latter being held in the backs 25 by retaining rods 34 (Figure 5). The rods 34 are secured at their opposite ends to the opposite ends of the backs or channel bars 25, as by securing them to a transversely bent portion of the channel bar 25 (not shown). Each bristle assembly 30 is cut away as at 35 (Figure 1) to form a slot through which split rings or hoops 36 may be passed. The rings 36 have eyes 37 at their opposite ends and clamping bolts 38 are passed through these eyes (Figure 2) in order to clamp the rings 36 tightly to the hub structure 11. Only two rings 36 are necessary and these merely prevent endwise motion of the brush units 12.

In the operation of the form of the invention shown in Figures 1 to 5 inclusive, let it be assumed that the rotary brush 10 has been assembled in the form shown therein and that the brushes have become so worn as to require replacement. To replace the brushes, the operator merely removes the two clamping bolts 38 from the eyes 37 at the ends of the rings 36, and then withdraws the rings 36 from the gaps or cutaway portions 35 of the bristle assemblies 30. He then removes each brush unit 12 from the hub structure 11 by sliding it endwise out of its respective notches 18 in the peripheries of the discs 15. New brush units 12 are inserted by reversing the above procedure, after which the rings 36 are reinserted and clamped by means of the clamping bolts 38. As previously stated, the brush backs 25 are held in position by the abutments or shoulders 21 formed by the overhanging edges 20 of the notches 18, so that the rings 36 are not called upon to hold the brush units 12 in place, other than to prevent endwise motion thereof. The rotary brush 10 can then be replaced in the machine and reconnected to the power source by which it is rotated. To replace the bristles 31 in each brush unit 12 (Figure 5), it is only necessary to remove the retaining rods 34, after which the bristles 31 can be pulled out or will readily fall out. New bristles can then be inserted in place of the worn bristles and the

retaining rod 34 replaced in the channel bar or back 25.

The modified rotary brush 39 shown in Figures 6 to 9 inclusive is similar in principle to the rotary brush 10 of Figures 1 to 5 inclusive, except that it has a rounded end. Similar parts are therefore designated with similar reference numerals in order to avoid needless repetition of description. The brush units 40 have brush backs or bars 25 provided with arcuately bent end portions 41, the ends 42 of which enter openings or notches 43 in the edge flange 44 of a crown disc 45 forming a holding member. The crown disc 45 is provided with a central hole 46 by which it is mounted upon the threaded reduced diameter end portion 47 of the shaft 13. A cup-shaped member 48 with an edge flange 49 is provided with a central hole 50 by which it is inserted upon the reduced diameter threaded portion 47 and held in place by nuts 51. The flange 49 thus holds the ends 42 of the bars 25 in the notches 43 of the crown disc 45. The bristles 31 forming the bristle assemblies 30 of the modified rotary brush 39 are mounted in the brush bars or channel backs 25 in the same manner as in the form of the invention shown in Figures 1 to 5 inclusive, except that the retaining rods 34 have arcuate portions at one end of each rod corresponding to the arcuate portions 41 of the brush backs 25.

The operation of the modified rotary brush 39 is similar to that of the rotary brush 10, with the exception of the fact that the brush units 40 can be withdrawn from only one end of the brush, due to the curvature of the brush units 40. To remove the brush units 40, therefore, the operator takes off the clamping ring 36, as before, removes the nuts 51 and the cup-shaped member 48 from the end of the shaft 13 (Figure 6), after which he grasps the ends 42 of the bars 25 and draws the brush units 40 out of the notches 43 in the disc 45 in the manner previously described. He then replaces the worn brush units 40 by new brush units by reversing the foregoing procedure, reapplies the cup-shaped member 48, and the clamping ring 36, as described above.

What I claim is:

1. A rotary brush comprising a hub structure having a shaft and a plurality of spaced brush mounting discs thereon, each brush mounting disc being of substantially circular outline with circumferentially-spaced undercut openings of approximately rectangular outline therein, brush units mounted in said openings, each brush unit having an elongated brush back of approximately channel cross-section with substantially parallel side walls inserted in its respective openings and a bristle assembly mounted in the channel of said back, said discs adjacent the mouth of each opening having shoulders overhanging and abuttingly engaging said brush back, each brush back being substantially straight throughout the major portion of its length and having an arcuately bent portion at one end thereof directed toward the axis of said hub structure, and a holding member secured to said hub structure and having end receiving portions adapted to receive the bent ends of said brush backs.

2. A rotary brush comprising a hub structure having a shaft and a plurality of spaced brush mounting discs thereon, each brush mounting disc being of substantially circular outline with circumferentially-spaced undercut openings of approximately rectangular outline there-

in, brush units mounted in said openings, each brush unit having an elongated brush back of approximately channel cross-section with substantially parallel side walls inserted in its respective openings and a bristle assembly mounted in the channel of said back, said discs adjacent the mouth of each opening having shoulders overhanging and abuttingly engaging said brush back, each brush back being substantially straight throughout the major portion of its length and having an arcuately bent portion at one end thereof directed toward the axis of said hub structure, a holding member secured to said hub structure and having end receiving portions adapted to receive the bent ends of said brush backs, and a locking member secured to said hub

5 structure externally of said brush back ends and securing said brush back ends in said end-receiving portions.
